UNITED STATES PATENT OFFICE.

BENJAMIN B. ENGLANDER, OF NEW YORK, N. Y., ASSIGNOR TO ENGLANDER SPRING BED COMPANY, OF BROOKLYN, NEW YORK, A CORPORATION OF NEW YORK.

TWO-MOTION DIVANETTE.

1,063,519.

Specification of Letters Patent.

Patented June 3, 1913.

Application filed January 18, 1913. Serial No. 742,823.

To all whom it may concern:

Be it known that I, BENJAMIN B. ENGLANDER, a citizen of the United States, residing at New York, borough of Manhattan, in the county of New York and State of New York, have invented certain new and useful Improvements in Two-Motion Divanettes, of which the following is a specification.

This invention relates to convertible divans or couch beds, more particularly to that class known as divanettes, the object of the invention being to provide an improved structure of this kind which may be opened to form the usual length of bed while it need only take up about four feet space along the wall, and which divanette in the form thereof shown comprises a multiplicity of bed sections all movable by one movement from one to the opposite side of a stationary frame or section and then by another movement to form a full length bed or closed to form a divan, and which structure is comparatively inexpensive to manufacture and is simple and easily operated.

In the drawings accompanying and forming part of this specification, Figure 1 is a perspective view of this improved divanette partly opened; Fig. 2 is a perspective view thereof entirely opened; and Fig. 3 is a detail view of one end of the structure.

Similar characters of reference indicate corresponding parts throughout the figures of the drawings.

In the preferred form thereof this improved divanette comprises a stationary frame or section relative to which a plurality of sections are moved, and which stationary frame at the proper time will support the back. This stationary frame or section 2 in the present instance comprises a pair of end frames 3 forming end arms 4 and legs 5 and 6, the rear legs 6 being suitably connected by lengthwise extending braces or bars 7 and 8. The legs at each end also are connected by a crosswise extending bar 9. Located for movement between these end frames 3 is a series of bed sections comprising a main or central section 10, to which are hinged a back section 20 and a front section 30 and which latter is connected with a front sliding section 40, the back section 20 and front sliding section 40 being also connected so that on the sliding forward of the section 40 the back 20 will

be thrown down on to the stationary frame 2.

The main section 10 comprises a pair of end frames 11 suitably braced and carrying a spring mattress 12. Connected to each end frame 11 is a pair of angle bars 13 and 13', which pass through straps 14 and 14' secured to the inner leg 5 of the stationary frame 2, by which means the movements of the several bed sections relatively to the frame 2 are guided and which also tend to suitably brace the forward legs 5 of the two end frames 3 so that no lengthwise extending braces are needed at this point.

Hinged to the rear side of the main section 10 is the back section 20 hereinbefore referred to, which likewise carries a spring fabric 21 and which when the structure is in the form of a divan forms the back thereof and when the structure is opened out rests upon the upper transverse bar 7 connecting the legs 6 of the stationary section 2. Secured to the opposite or front side of the main section 10 is a U-shaped bar 31, this being pivoted at its ends to the end frames 11 of said section 10, and this bar carries one part of a sectional mattress, as 32, one edge of which is connected to another section of such sectional mattress, as 15, which in turn is connected to the section 22 forming part of the back. This front bed section 30 when the structure is in the form of a divan normally rests on top of the stuffed mattress 15 of the section 10 to form the seat.

Located under the spring 12 of the main or central section 10 is the sliding front section 40 hereinbefore referred to, and this sliding section is connected at each end by a linkage connection 41 with the U-shaped bar 31 forming the section 30, so that on manipulating this bar of the section 30 the front sliding section will be pushed forward or returned under the main or central section 10. This front sliding section is made up in a similar manner to the main or central section 10, and therefore comprises a pair of end frames 42 suitably connected and provided with the usual spring 43. Connecting the back section 20 with the front sliding section 40 is another linkage connection 21, one at each end, and this linkage connection comprises a depending member 25 connected to the back and linked by a member 26 with the front sliding sec-

tion 40, so that on manipulating the section 30 the front sliding section 40 will be moved forward or backward and at the same time the back will be raised or lowered, a suitable spring 50 being shown for assisting the manipulation of the back.

By means of the present improvement the structure may be utilized without pulling the same from the wall, which is a very desirable feature in an article of this kind. In practice the main or central section 10 and front sliding section 40 are provided with casters 51.

When the divanette is in the form of a divan the back 20 is of course in a raised position, the seat section 30 is resting upon the main or central section 10 and the front sliding section 40 is under such section 10, while all of such sections are between the end frames 3 of the stationary section 2, which of course is usually against the wall. The user, by grasping any convenient part of the structure, pulls the sections 10 and 40 forward on their casters from between the end frames 3 of the stationary section 2 and therefore to the front side thereof, as shown in Fig. 1, in which position the structure is in readiness to be opened to form a double bed and then by manipulating the U-shaped bar forming part of the section 30 the front sliding section 40 is shifted outwardly into the position shown in Fig. 2, where it will receive the stuffed mattress 32, and at the same time the back 20 is thrown down and is supported by the lengthwise extending side bar 7 of the end frames 3 of the stationary section 2. By shifting the bar 30 from the position shown in Fig. 2 so that it will carry the stuffed mattress 32 on top of the stuffed mattress 15 to form the seat the front sliding section 40 will be shifted inwardly under the section 10 and the back section 20 will be raised, whereupon the user merely shifts the same backward and into the space between the end frames 3 of the stationary section.

From the foregoing it will be observed that the present improved bed structure comprises a series of three telescopic sections, two of which are shiftable or slide relatively to a stationary section and one of which shifts relatively to its companion shiftable section, and one of which telescopic sections, as for instance what may be considered the middle or central one when the structure is opened, carries a pair of swinging sections one in the form of a mattress and the other in the form of a back, the bed being opened or closed by two motions, one pulling out the telescopic sections to the front of the stationary section and the other by moving the back or the reversible section, whereupon the bed structure is opened in the form of a full length bed as

shown in Fig. 3 or closed in readiness to form a divan, whereupon the telescopic sections may be returned to their original position to form such divan.

I claim as my invention:

1. A divanette comprising a stationary section or frame, a pair of sliding sections movable relatively to said stationary section both to extend beyond one side of said stationary section and one sliding section to extend beyond the other, each of said sliding sections including an independent spring and comprising in itself a complete bed structure so that each spring is in every position of its section under tension and in its normal mattress supporting position, and a back hinged to one of said sliding sections and adapted to be supported by the stationary section when the back is in its lowered position.

2. A divanette comprising a stationary section or frame, a pair of sliding sections movable relatively to said stationary section both to extend beyond one side of said stationary section and one sliding section to extend beyond the other, and a reversible section hinged to one of said sliding sections and adapted to be supported by the other sliding section.

3. A divanette comprising a stationary section or frame, a pair of sliding sections movable relatively to said stationary section both to extend beyond one side of said stationary section and one sliding section to extend beyond the other, a back hinged to one of said sliding sections and adapted to be supported by the stationary section when the back is in its lowered position, and a reversible section hinged to one of said sliding sections and adapted when reversed to be supported by the other sliding section.

4. A divanette comprising a stationary section, a pair of sliding sections movable relatively thereto to extend beyond one side of said stationary section, one of said sliding sections being under the other, a back hinged to one of said sliding sections, and a reversible section hinged to the opposite side of the same sliding section and adapted to be supported by the other sliding section when the structure is extended to form a bed.

5. A divanette comprising a stationary section or frame, a pair of sliding sections movable relatively thereto from one side to the other thereof, one comprising a central sliding section and the other a front sliding section, a back hinged to said central sliding section and adapted to be supported by said stationary section when such back is lowered, a reversible section also hinged to said central sliding section and adapted to be supported by said front sliding section when reversed, and means connecting the reversible section with the front sliding section.

whereby the latter is shifted on the reversal of said reversible section.

6. A divanette comprising a stationary section, a pair of sliding sections movable relatively thereto to extend beyond one side of said stationary section, one of said sliding sections being under the other, a back hinged to one of said sliding sections, a reversible section hinged to the opposite side of the same sliding section and adapted to be supported by the other sliding section when the structure is extended to form a bed, and means connecting one of said sliding sections with the back whereby when said sliding section is operated the back will be raised or lowered.

7. A divanette comprising a stationary section, a pair of sliding sections movable relatively thereto to extend beyond one side of said stationary section, one of said sliding sections being under the other, a back hinged to one of said sliding sections, a reversible section hinged to the opposite side of the same sliding section and adapted to be supported by the other sliding section when the structure is extended to form a bed, and means connecting the back with the under sliding section whereby when the latter is shifted the back will be raised or lowered.

8. A divanette comprising a stationary section or frame, a pair of sliding sections movable relatively thereto from one side to the other thereof, one comprising a central sliding section and the other a front sliding section, a back hinged to said central sliding section and adapted to be supported by said stationary section when such back is lowered, a reversible section also hinged to said central sliding section and adapted to be supported by said front sliding section when reversed, means connecting the reversible section with the front sliding section whereby the latter is shifted on the reversal of said reversible section, and means connecting the back with said front sliding section whereby when the latter is shifted the back will be raised or lowered.

9. The combination of a stationary section or frame, a pair of sliding bed sections connected with said stationary section and shiftable relatively thereto from one side to the other and each having a spring, a back section also having a spring and connected to one of said sliding sections, a reversible mattress section connected with the same sliding section and adapted in one position to form the seat and when reversed to be supported by the other sliding section, means connecting the reversible section with

one of the sliding sections, and means connecting one of the sliding sections with the back section whereby on shifting one of the sections two other sections will be shifted.

10. The combination of a stationary section or frame and a series of four sections movable relatively thereto from one side to the other, and means connecting said movable sections together whereby on the shifting of one of them two others will be shifted, 65 said four sections comprising a pair of swinging sections and a pair of sliding sections.

11. The combination of a stationary section or frame and a series of four sections 75 movable relatively thereto from one side to the other, means connecting said movable sections together whereby on the shifting of one of them two others will be shifted, said four sections comprising a pair of swinging 80 sections and a pair of sliding sections, and means connecting one of the sliding sections with the stationary section.

12. The combination of a stationary section or frame and a series of four sections 85 movable relatively thereto from one side to the other, means connecting said movable sections together whereby on the shifting of one of them two others will be shifted, said four sections comprising a pair of swinging 90 sections and a pair of sliding sections, and means connecting one of the sliding sections with each end of the stationary section.

13. A bed structure comprising a series of three sections one telescoping within another 95 and one of said sections carrying a swinging back adapted to be supported in its lowered position by another of said sections, said section also carrying a swinging section adapted in one position to form the seat and 100 in another position to be supported by another of said sections.

14. A bed structure comprising a series of three sections one telescoping within another and one of said sections carrying a 105 swinging back adapted to be supported in its lowered position by another of said sections, said section also carrying a swinging section adapted in one position to form the seat and in another position to be supported 110 by another of said sections, and means connecting all of said sections together whereby on the manipulation of one two others will be shifted.

Signed at Brooklyn, N. Y., this 16th day 115 of January, 1913.

BENJAMIN B. ENGLANDER.
